UNITED STATES PATENT OFFICE.

CHARLES LYMAN LOFFLER, OF DENVER, COLORADO.

ATTACHMENT FOR SYRINGES.

1,147,179.

Specification of Letters Patent. Patented July 20, 1915.

Application filed January 9, 1914. Serial No. 811,217.

To all whom it may concern:

Be it known that I, CHARLES L. LOFFLER, a citizen of the United States, residing at Denver, in the county of Denver and State 5 of Colorado, have invented certain new and useful Improvements in Attachments for Syringes; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15 This invention relates to improvements in what may be termed rectal injectors, particularly employed in administering internal baths through the rectum.

20 The invention has for its object, primarily, to greatly simplify and render light the construction of the parts and yet provide for the retention of the requisite durability and stability in use or application.

25 A further object is to provide for forming an effective and ready connection between the solution or liquid supply tubing and the rectal administering tube or nozzle elbow.

30 A still further object is to afford stability and strength at the point of attachment between the rectal nozzle or tube and the base-member.

35 A still further object is to carry out the aforesaid ends in a simple, expeditious and effective manner.

The invention consists of certain instrumentalities and features substantially as hereinafter fully disclosed and defined by 40 the appended claims.

In the accompanying drawing is illustrated the preferred embodiment of my invention, wherein it will be understood that various changes and modifications may be 45 made as to the detailed construction and arrangement of the parts without departing from the spirit thereof and covered by the scope of the claims, and in which drawing—

50 Figure 1 is a broken perspective view showing an internal bath outfit or plant embodying my invention. Fig. 2 is a partly elevational and partly sectional view with the initial liquid or solution supply tubing 55 shown fragmentarily and other parts broken away.

In carrying out my invention, I employ a tubular base 1, preferably circular or of helical-like or convoluted outline having a lateral or right-lined extension 2, itself having a terminal 3 formed with an external enlargement or shoulder 4, the latter facing inwardly or toward the basic member 1 and having an oppositely tapering surface, the same vanishing into the outer surface of that end of the terminal 3. This construction provides for the expanding or distending of the elastic or rubber solution-supplying pipe or tubing 5 over the shoulder equipped terminal 3, 4, of the tubular basic 60 member 1 as seen particularly in Fig. 2, whereby an effective connection is formed therebetween, and which connection is effected with great facility and without the use or aid of other fastening means of any 65 kind whatsoever which obviously are desiderata in applying and removing the solution supplying tubing or medium, the latter leading from the liquid or solution holding bag or chamber 6 preferably of the well 70 known elastic or collapsible type.

An upright thickened-walled rubber nozzle or tube 7, having in addition to its usual upper open end outlet 8 a number of lateral jet-delivering apertures 9 suitably arranged in the thickened walls of said nozzle near said upper open end for advantageously delivering or distributing the solution as it leaves or is discharged from the rectal tube or nozzle as will be readily understood. 75 The nozzle or tube 7 is adapted to be fitted snugly upon the upstanding portion of an elbow terminal 10 of the basic member 1, said upstanding portion extending centrally from the inwardly curved or extending terminal of the latter, the rectal nozzle with said upstanding or attaching member therefor being thus adapted to be adjusted to and to enter the rectum, and the basic member to conform to the arms or buttocks for holding the nozzle centrally within the rectum. The rectal nozzle or tube 7 has its lower end portion further thickened or flared downwardly in preferably frusto-cone-like outline as at 11 for widening said end or 80 base for obvious reasons, said base-end resting preferably upon a conforming plate or member 12, itself resting directly upon the inwardly extending or curved terminal of the basic member 1.

I claim:

1. A device of the type described, includ-

ing a skeleton-like flat formed tubular base having an upstanding central extension or terminal, and a rectal nozzle applied to said upstanding terminal of the base, said tubular base being of flat spiral form, said upstanding extension terminating said tubular base centrally thereof.

2. A device of the type described, including a flat spiral tubular member adapted to 10 form a base, the same having a central upstanding elbow or terminal, and a rectal rubber nozzle fitted upon said upstanding terminal, said rubber nozzle having a flared base.

15 3. A device of the type described, including a flat spiral tubular basic member, carrying an upstanding central tubular terminal and a terminal having an external shoulder or enlargement facing inwardly or toward the center of said basic member, said 20 shoulder tapering oppositely upon its outer

surface for insertion into an expandible solution-feeding or supplying tubing, and a rectal nozzle applied to said upstanding central tubular terminal of the basic member, said nozzle having a flared base.

25 4. A device of the type described, including a tubular basic member of flat spiral form and having a central upstanding tubular terminal, means for supplying the same 30 with a liquid solution, and a rectal rubber nozzle with perforated thickened walls at its upper end, the lower end portion of said rectal nozzle being further thickened and flared downwardly to its base.

35 In testimony whereof, I affix my signature in presence of two witnesses.

CHARLES LYMAN LOFFLER.
